UNITED STATES PATENT OFFICE.

FRANK WOLF, OF NEW YORK, N. Y.

DISPLAY-CABINET.

1,382,704.

Specification of Letters Patent. Patented June 28, 1921.

Application filed April 4, 1919. Serial No. 287,411.

To all whom it may concern:

Be it known that I, FRANK WOLF, a citizen of the United States, and a resident of the borough of Manhattan, in the city, 5 county, and State of New York, have invented certain new and useful Improvements in Display-Cabinets, of which the following is a specification.

The present invention relates to display 10 cabinets, and particularly such cabinets for use in the display of sample cards containing cloth samples, although it will be understood that the same contemplates other articles to be displayed as for instance pictures or the like. An object of the invention is to provide a display cabinet in which the sample cards may be displayed to the best advantage and in which a relatively great number may be stored and arranged 15 or assorted as desired and which will permit of a prospective purchaser making a selection with facility and without the necessity of handling the cards to any great extent.

A further object is to provide such a 20 cabinet which will protect the sample cards from wear, distortion and dust when not being displayed and which will contain them in a neat and orderly manner.

With these and other objects in view, em- 25 bodiments of my invention are shown in the accompanying drawings, and these embodiments will be hereinafter more fully described with reference thereto and the invention will be finally pointed out in the 30 claims.

In the accompanying drawings:

Figure 1 is a perspective view of one form 35 of cabinet embodying my invention, the same being closed;

Fig. 2 is a front elevation thereof in open 40 or display position;

Fig. 3 is a vertical sectional view taken through one end of the cabinet;

Fig. 4 is an upper end view of one of the 45 doors;

Fig. 5 is a front view of a modified form of cabinet according to my invention;

Fig. 6 is a vertical sectional view thereof 50 taken along the line 6—6 of Fig. 5; and

Fig. 7 is a plan view thereof.

Similar reference characters indicate corresponding parts throughout the several figures of the drawings.

Referring to the drawings and more par- 55 ticularly to Figs. 1 to 4 thereof, the embodiment of my invention shown therein

comprises a cabinet having an upright back 10, a base 11 and sides 12 and 13, the front edge of the said sides extending for a short distance above the base parallel to the rear 60 edge as at 14 and for the remainder of its length is inclined as at 15 to the narrow molding top 16. The open side of the cabinet is adapted to be closed by three doors, a lower door 17 hinged to the base at 17^a and 65 17^b and extending over the portion 14 of the sides and adapted to be swung forwardly and downwardly, and two outwardly swinging doors 18 and 19 extending from the top of the door 17 to the molding top 16, 70 the same having hinges 18^a and 18^b, and 19^a and 19^b concealed in the closed position of the door, and having their respective halves secured to the inner sides of the doors and to the inclined forward surfaces of the 75 sides 12 and 13, so that in the open position of the doors, the hinged upright ends will abut against the outer surfaces of the sides 12 and 13 thereby supporting the doors in a rearwardly inclined position flush and 80 in the same plane with the said forward inclined surfaces of the sides, this arrangement maintaining the position of the doors. The door 17 is provided with a knob 17^c and at its side with pivoted catch hooks 17^d 85 adapted to engage pins 17^e in the sides of the cabinet.

A central upright partition 20 is provided in the cabinet conforming at its forward end to the forward ends of the sides 12 and 90 13 but terminating at a point below the upper end of the cabinet, the upper end being curved rearwardly to the back 10 as at 21. In the closed position of the doors the meeting ends rest upon the forward inclined portion of the partition, their rearward inclination preventing opening. Knobs 22 and 23 are respectively provided upon the doors 18 and 19 and if desired they may be provided with suitable catches or locks. The doors 100 18 and 19 are of rectangular frame shape being grooved at the inner surfaces of the base and sides as at 24, while the top is provided with a slot 25 in continuation of the grooves of the sides to enable the insertion 105 of panels 26 containing upon each side suitable advertising matter or illustrations relating to the articles to be displayed. These panels are removable and may be renewed when desired or in the case of cloth samples 110 they may be renewed for each season as the styles change. Upon their inner sides, the

doors are provided with a plurality of spring clips 27 for holding the sample cards 28 upon the doors in an advantageous position to be examined in comparison with 5 other samples. These clips it will be understood are only utilized when the doors are open.

The lower door 17 is beveled at its inner longitudinal side and is hinged intermediate 10 the upper and lower edges of the beveled front side of the base, so that in the closed position (Fig. 1) the inner side engages the upper portion of the beveled front side of the base while in the open position the door 15 does not project above the upper surface of the base.

Above the base and spaced therefrom and extending forwardly from the back 10 there is provided at each side of the partition 20 a 20 horizontal shelf 29 and rearwardly of the forward edge of said shelf there is provided an upright backing member 30 supporting at its upper end a second horizontal shelf 31 extending from the said backing member to 25 the back 10, the two shelves being in stepped arrangement relatively to each other.

Metal corner pieces 32 of right angular shape are provided at the ends of the forward edges of the shelf and are secured at 30 their side portions to the sides 12 and 13 and the partition 20 of the cabinet by tacks 33, and in spaced relation from each other and upon each of the shelves there are provided a pair of strips 34 and 35 spaced from the 35 ends of the shelves and having their upper surfaces downwardly and rearwardly inclined.

In the free spaces 36 below the shelves 29, a relatively large number of the sample 40 cards 28 may be placed in flat position. Upon each of the shelves a plurality of sample cards are supported uprightly, the strips 34 and 35 inclining them slightly backward so that they may be viewed to the best advantage. The cards are of such size that the upper edges of those cards supported upon the shelves 29 extend slightly above the lower edges of the cards supported upon the shelves 31. The shelves are so disposed 45 relatively to the inclined front of the cabinet that should they be filled to capacity with cards, the front card as indicated in dotted lines (Fig. 3) will be spaced from and protected from contact with the doors 18 and 19 50 when closed.

The under side of the molding top 16 is provided with a longitudinal slot 37 in which is received the upper edge of a display card 38, the side edges and the lower edges 60 being supported by contact with the sides of the cabinet and the upper end of the partition 20. This card may be readily removed and renewed when desired.

When the cabinet is closed, the sample 65 cards are thoroughly protected from dust

and are supported in a manner as to protect the samples and maintain the shape of the cards. When open, the cards are advantageously displayed to permit of the selection of samples with the greatest facility, it 70 being possible to successively remove the front cards and place them at the rear without handling the cards to any great extent. Preferably samples of one class will be placed upon the respective shelves, that is 75 for instance, black cloth samples may be placed upon one shelf, blue cloth samples upon another shelf, etc. The spring clips 27 enable a sample card removed from the shelf, to be supported in a convenient position to be compared with other sample cards 80 and in fact several cards may be so supported upon the doors at the same time.

In Figs. 5 to 7, I have illustrated a modified form of my invention in which the cabinet comprises a back 50, a base 51, sides 52 and 53 having their forward edges stepped as at 54, 55 and 56, and a central upright partition 57. At each side of the partition there is provided rearwardly of the forward end of the base an upright support 58 at the upper end of which there is provided a horizontal shelf 59 extending to the back 50, and upon this shelf and rearwardly of its forward edge there is provided a second upright support 60 having at its upper end a second horizontal shelf 61 extending to the back 50. The forward edge of the partition extends perpendicularly as at 62, 63 and 64 for a short distance above the base 51 and the shelves 59 and 61, the portions of the forward edges above the perpendicular portions being curved as at 65, 66 and 67, the curved portions 65 and 66 terminating above the lower end of the portions 63 and 64, slots 68 and 69 being provided therebetween. Metal retaining plates 70, 71 and 72 projecting at each side of the partition 57, are secured by tacks 73 to the perpendicular portions 62, 63 and 64, the plate 70 being held at its forward side by a molding piece 74 extending along the forward edge of the base, while the plates 71 and 72 are disposed in the slots 68 and 69. At the outer ends of the shelves there are provided right angular metal corner pieces 75 secured at their side portions to the sides 52 and 53 of the cabinet.

Upon the base 51 and the shelves 59 and 61 there are provided spaced strips 76 inclined at their upper surfaces in a similar manner to the strips 34 and 35 of the form of my invention illustrated in Figs. 1 to 4. A plurality of the sample cards are placed upon each shelf being held by the retaining pieces and inclined rearwardly by the 125 strips 76.

The back 50 projects above the cards as at 50^a to provide a suitable space to contain advertising matter. If desired, the portion of the cabinet below the shelf 59 may be 130

made free as in the first form of my invention to provide an open compartment so that cards may be placed horizontally therein.

It will be particularly noted in the embodiments shown and described, that the display cabinets show stepladder units which enable the display cards to be shown stepladder fashion. As a result of this, the display cards can be suitably arranged in accordance with the quality of the cloth or the colors thereof. So, for instance, if it is desired to arrange the display cards so that all samples of the same color are together, this can be done by arranging all of the same color on one shelf. Similarly if it is desired to classify the display cards in accordance with the quality of the display samples attached to the cards, this can also be done by arranging different groups on different shelves. It will also be particularly noted that the display cards rest upon a very narrow surface, as for instance, on the strips 76. The advantage of these narrow supporting strips prevents very little frictional surface with the edge of the cards and thereby a wearing away of the edge of the display card is obviated. At the same time, the use of such spaced strips prevent a rocking of a card which might otherwise result if a card having an irregular edge is placed upon a flat surface. By inclining these strips in the manner shown in the drawings, the positioning of the display cards which would result in an irregular manner due to the interposed strips of cloth attached to the display cards, is compensated so that the cards with the display surface always maintain a proper position. It will also be noted that the upper edge display cards of a lower shelf extend beyond and above the lower edge of the cards on the shelf immediately above. By this arrangement, the capacity of the cabinet is greatly increased, the overlapping feature being not sufficient to depreciate the efficiency of the operation.

It will also be noted that the brackets that hold the display cards cover only the lower-most corners of the display cards and by reason of this the entire remaining surface of the display cards is exhibited to view.

By the arrangement of the stepladder method combined with the ridges which support the display cards and the corner retaining means for the display cards, a device is provided which enables display cards to be efficiently shown in that such display cards might be readily distributed in the display cabinet for exhibition purposes and at the same time may be readily taken out of the display cabinet for the replacement of other cards or personal examination of the samples attached to the display cards.

The embodiments of my invention which I have described, present advantageous fea-

tures over the use of display cards as hitherto proposed. Heretofore it has been customary to supply the dealer with large quantities of display cards to which pieces of cloth are attached, which supply runs into considerable expense. The dealer would keep such display cards in most any cardboard box which would soon break down under wear and tear and as a consequence the display cards would become lost or soiled or so destroyed as to be incapable of use for an intended purchaser. Considerable replacement of such display cards was therefore required which, in the aggregate throughout the year, runs into considerable expense. The use of my improved display cabinets obviates these disadvantageous features in that by the use of a cabinet of this kind, such a cabinet can be forwarded to a user, containing a full line of display cards and immediately on receipt thereof, the user can set it up in position for display purposes. The use of such a cabinet insures the cards being maintained and retained in their proper places and by the advantages resulting, the perspective purchaser may have before him a complete line of display cards suitably exhibited and substantially always in good condition.

I have illustrated and described preferred and satisfactory embodiments of my invention but it is obvious that changes may be made therein within the spirit and scope thereof as defined in the appended claims.

I claim:

1. In a display cabinet, an upright back, a plurality of stepped shelves disposed forwardly of said back adapted to support cards, retaining means at the forward edge of said shelves adapted to retain the lower corners only of the cards, and hold the cards uprightly and exposed upon said shelves, and means on said shelves adapted to support said cards at spaced points.

2. In a display cabinet, an upright back, a plurality of stepped shelves disposed forwardly of said back, retaining means at the forward edge of said shelves adapted to retain cards uprightly and exposed upon said shelves, and a pair of spaced strips on each of said shelves having their upper surfaces inclined and adapted to incline said cards rearwardly.

3. In a display cabinet, an upright back, a plurality of stepped shelves disposed forwardly of said back adapted to support cards, retaining means at the forward edge of said shelves adapted to retain the lower corners only of the cards and hold the cards uprightly and exposed upon said shelves, and means on said shelves adapted to support said cards at spaced points, said means being inclined and adapted to incline said cards toward said back, the plane of in-

clination of said cards being substantially at right angles to the plane of the inclined surfaces of said means.

4. In a display cabinet, an upright back, 5 side walls, and a central partition extending forwardly and at right angles to said back, a plurality of stepped shelves disposed forwardly of said back at each side of said partition, the lowermost shelf being forwardly 10 of the uppermost shelf, spaced-apart supports arranged upon the shelves and having rearwardly and downwardly inclined upper

edges adapted to support cards at a rearward inclination, and retaining means carried by said side walls projecting over the 15 forward edge portion of the shelves to engage and maintain cards on the supports of the shelves and with their outer faces unobstructed.

In testimony that I claim the foregoing 20 as my invention, I have signed my name hereunder.

FRANK WOLF.
